DESIGN FOR A SWEATER

Daniel Rheinauer, New York, N. Y.

Application December 10, 1934, Serial No. 54,384

Term of patent 14 years

To all whom it may concern:

Be it known that I, Daniel Rheinauer, a citizen of the United States, residing at the Borough of Manhattan, in the city, county, and State of New York, have invented a new, original, and ornamental Design for a Sweater, of which the following is a specification, reference being had to the accompanying drawing, forming part thereof.

Fig. 1 is a rear elevational view of a sweater showing my new design.

Fig. 2 is a side elevation of the same on a reduced scale.

The characteristic feature of the design resides in the arrangement of the different types of knitting across the shoulders of the sweater from the arm to the neck and across the back of the sweater at the waist-line between the side seams of the sweater resulting in a pinch back and pleated appearance.

I claim:

The ornamental design for a sweater, as shown and described.

DANIEL RHEINAUER.
